UNITED STATES PATENT OFFICE.

WALTER S. FRAZIER, OF AURORA, ILLINOIS.

SULKY.

SPECIFICATION forming part of Letters Patent No. 238,744, dated October 26, 1880.

Application filed May 10, 1880. (No model.)

To all whom it may concern:

Be it known that I, WALTER S. FRAZIER, residing at Aurora, in the county of Kane and State of Illinois, and a citizen of the United States, have invented a new and useful Improvement in Sulkies or other Two-Wheeled Vehicles, of which the following is a full description, reference being had to the accompanying drawings, in which—

10 Figure 1 is a side elevation with a wheel removed, and Fig. 2 a bottom or under view view with one of the foot-board bars broken partly away.

15 The object of this invention is to provide a sulky or other two-wheeled vehicle with a spring-seat and a floor-board platform or foot-rest to move with the seat and relieve the feet and knees from the jarring action of a spring-seat, combined with a fixed platform or foot-board; and its nature consists in attaching 20 one end of the feet-supporting device to the shafts or other fixed part or parts of the vehicle and supporting the other end from the spring-seat or the seat-supports by means of 25 rods or equivalent device or devices, as herein-after described.

30 In the drawings, *a* indicates the axle of a sulky; *b*, the wheels; *c*, the shafts; *d*, the seat-supports; *e*, the seat; *f*, the connecting rod or rods; *g*, platform or foot-rest supports; *h*, platform or foot-rest; *i*, springs; *j*, links or attaching couplings or clips; *k*, hinges, and *l* a cross-bar for connecting the shafts together.

35 The wheels, axle, and shafts are made in any of the usual or well-known forms in the ordinary manner.

40 The seat, which may be single or double and of any desired form, is supported upon the bars *d*. These bars have their front ends placed under the links *j*; but it is obvious that hinges, eyebolts, or other flexible connecting devices may be used and these bars pass over rubber or other suitable springs *i*. I deem this a better form than to make the 45 bars *d* spring-bars and pass them over fixed fulcra.

The platform or foot-rest *h* is supported on bars *g*, which bars, as shown, are hinged at *k* to the shafts by common strap-hinges; but any

kind of hinge down to a leather one will answer the purpose, and the bars may be hinged to the shafts at any desired point along their length, or to the cross-bar *l*. Their rear ends are supported from the seat or seat-bars by the rods *f*, which connect them with the bars *d*; but it is evident a single rod connecting the seat with the platform at the middle may be made to take the place of the two rods shown. These rods may be simple rods, or one end may be provided with a screw-thread and a nut, the purpose being to connect one end of the platform with the seat or its supports, so that the two will maintain the same relative position to each other; or nearly the same.

45 When the nut and screw-threaded rod or rods are used the distance between the foot-rest and seat may be varied or adjusted to suit different persons.

50 The operation will be apparent from the description.

I do not limit myself to rods for connecting the foot-rest with the seat. This might be done by means of wood framing, by chains, or straps.

55 It is not necessary that the front of the foot-rest be connected with some part by a hinge. Usually a flexible connection will be desirable; but in some cases a connection which is rigid, or nearly so, may be used.

60 By giving the bars *g* a curved, bent, or angular form, as shown, a short bar can be used and the required distance between the seat and foot-rest be maintained without any inconvenient slant or inclination that would be objectionable in use. The forward ends of these bars can have a still shorter curve than that shown, or a bend or upward turn, in which case the point of attachment of their forward ends can be still farther back and not produce any inconvenience in use. Straight bars, if used, would need to be much longer and be attached still farther forward in order to maintain the proper distance between the seat and foot-rest and avoid the objection of too much slant or tilt.

65 The construction of my improved sulky is simple and strong, and it obviates the neces-

sity of any framing or supports between the axle and seat, and also any lengthening out of the vehicle as a whole.

What I claim as new, and desire to secure 5 by Letters Patent, is—

1. In a sulky or two-wheeled vehicle having its shafts connected with the axle and a seat supported by the shafts, the combination of a curved or bent movable foot-rest support with 10 one or more rods or straps, *f*, supporting the rear end of such foot-rest, substantially as specified.

2. The combination of the supports or bars *d*, fulcrum-springs *i*, and shafts *c* with the

hinged and curved foot-rest bars *g* and one or 15 more connecting rods or straps, *f*, substantially as set forth.

3. In a sulky or two-wheeled vehicle, the combination of a spring-seat and a suspended foot-rest with the shafts *c*, upon which both 20 are supported, whereby the seat parts are free at their rear ends and independent of any supporting-axle connection, substantially as shown and described.

WALTER S. FRAZIER.
